UNITED STATES PATENT OFFICE.

TRUE M. AVERY, OF GLENS FALLS, NEW YORK, ASSIGNOR TO UNION BAG & PAPER CORPORATION, OF NEW YORK, N. Y., A CORPORATION OF NEW JERSEY.

BAG-PACKAGING PRESS.

1,359,311.

Specification of Letters Patent. Patented Nov. 16, 1920.

Application filed February 10, 1919. Serial No. 276,089.

To all whom it may concern:

Be it known that I, TRUE M. AVERY, a citizen of the United States, residing at Glens Falls, in the county of Warren and State of New York, have invented new and useful Improvements in Bag-Packaging Presses, of which the following is a specification.

This invention relates to an improved press especially applicable to the work of baling or packaging paper bags and the principal objects of the invention are to promote speed and facility of operation, to provide for automatic operations at all times and in all respects completely under the operator's control and to provide a press which shall be readily adaptable to bags and bag packages of varying proportions and which will be sturdy, durable and relatively compact.

The invention relates more particularly to a pneumatically operated press, and with the stated objects in view the invention resides in certain features of structure, combination and relation involving the co-operating elements whereby the pneumatic operation of the press is carried out, and also in certain other details of structure and arrangement, tending to promote facility of use, all of which features will be set forth at length as the description proceeds.

An embodiment of the invention is illustrated in the accompanying drawings, wherein:

Figure 1 is a plan view of a press in which the features of the invention are incorporated, the active part or plunger being in its retracted position.

Fig. 2 is a side elevation.

Fig. 3 is an elevation from the rear end of the press.

Fig. 4 is a detail vertical sectional view of the pneumatically operated plunger and its appurtenances.

Fig. 5 is a detail elevation, partly in section, on the line 5-5 of Fig. 4.

Fig. 6 is a detail cross-sectional view to a somewhat enlarged scale on the line 6-6 of Fig. 1.

Fig. 7 is a detail perspective view of an element of the table upon which the bags are packaged or baled.

Fig. 8 is a detail cross-sectional view to a somewhat enlarged scale on the line 8-8 of Fig. 4.

55 Figs. 9 and 10 are horizontal sectional

views on the respective lines 9-9 and 10-10 of Fig. 8.

Figs. 11 and 12 are detail vertical sectional views on the respective lines 11-11 and 12-12 of Fig. 8.

Fig. 13 is a detail elevation showing the working face of the controlling valve.

Similar characters of reference designate corresponding parts throughout the several views.

The operating parts are supported at a suitable elevation by a frame 1 which carries a bed plate 2, said frame and bed plate providing a table.

The bags to be packaged are supported at the front end of the bed plate 2 and are arranged vertically in a group and are disposed transversely, resting on their side edges, the group of bags being compressed to form a package of the dimensions desired by and between a fixed head 3 and a movable head of which 4 is a general designation. The fixed head 3 consists of a vertical transversely disposed plate arranged at the front end of the table and its dimensions are selected with regard to the dimensions of the bags which make up the package. The platform 2 preferably has at its front end a depending extension 5 to which the plate 3 is secured by fastening screws 6. Said plate may be provided with vertical slots 7 through which said screws extend and which enable vertical adjustments of the position of said plate, as may be desired, in accordance with the vertical dimension of the bags as laid on their side edges. The movable head 4 consists of a plate 8 which is carried by the reciprocating plunger 9 and a spring pressure bar 10 which is supported by but spaced from the plate 8. For the support of the bar 10 a bracket 11 is secured at one end of the plate 8 by a suitable fastening 12 and the bar 10 is secured at the front of the bracket 11 by a suitable fastening 13. The bar 10 has its other end free, and, being springy or resilient, has a yielding action at its free end. Such yielding action is, however, restricted or arrested by an abutment 14 which is spaced slightly to the rear of the bar 10 and which is secured by a suitable fastening 15 to the plate 8 at the end thereof remote from the bracket 11. The plate 8 is secured by fastenings 17 to the attachment flange 18 at the front end of the plunger 9 and is provided with horizontal slots 16.

through which pass the bolts of the fastenings 12 and 15 above referred to. It is preferred to provide for adjustments laterally and vertically of the position of the pressure bar 10 in order that the action of said bar may best be adapted to a bag of particular dimensions; and for this purpose, the bracket 11 may be formed with a horizontal slot 19 through which the bolt of the 5 fastening 12 extends and which provides for the lateral adjustment of the bar 10, and with a vertical slot 20 through which the bolt of the fastening 13 extends and which provides for the vertical adjustment of the 10 bar 10. The attachment flange of the abutment 14 may be formed with a horizontal slot 21 through which the bolt of the fastening 15 extends and which provides for a lateral adjustment of the position of said 15 abutment to compensate for a lateral adjustment of the position of the bar 10.

In the use of the press, the bags to be packaged are placed on edge parallel to the head 3 and bar 10 on a sheet of paper which 20 provides the wrapper, and cords are tied at suitable intervals about the package. To promote such use, the bed plate 2 carries at its front end and immediately in the rear of the head 3 a baling platform, of which 25 22 is a general designation and whose office is to provide an appropriate resting surface for the purpose in view. The platform 22 preferably consists of a pair of plates 23 mounted for transverse adjustment on the 30 bed plate 2. As shown, said bed plate is provided with a pair of transverse grooves 24 extending in parallel relation between the sides thereof and each plate 23 is provided along its under face and in laterally projecting relation with a tongue 25 which fits and is adjustable in one of the grooves 24, the projecting portion of each tongue extending under the companion plate 23 and being formed with a longitudinal slot 26 35 through which passes the bolt or shank of the fastening 27 employed for the connection of the tongue to the bed plate 2, such slot enabling suitable lateral adjustments of the 40 positions of the plates 23. The number of 45 cords employed for tying the package will be a matter of choice and will be dependent on the dimensions of the bags and the dimensions of the package, large bags and large packages obviously requiring more 50 securing cords than smaller ones. In any case, the head 3 will be provided with vertical slots 28 extending from its upper edge and affording cord guides and the plates 23 will be provided with longitudinal grooves 29 55 through which the cords are led, said grooves, of course, alining with the particular slots 28 which are used as cord guides. It will be obvious that the number and relative spacing of the slots 28 and the width of 60 the grooves 29 will be selected with regard 65

to the number and relative spacing of the cords by which the package is to be secured. The balls of cord may be arranged in a receptacle supported under the bed plate 2 by means of a shelf or platform carried by the 70 frame 1; and the cords will be passed through holes 30 in the bed plate 2 somewhat in the rear of the platform 22 and through holes 31 in the plates 23 and will thence be led through the grooves 29 and 75 slots 28, the plates 23 having flaring recesses 31^a in their under faces which lead to the holes 31 and afford clearance for the cords.

The plates 23 are preferably provided at their sides with hinged wings or flaps 32 80 which normally rest in horizontal positions upon supporting brackets 33 secured to the framing of the table 1 and may be suitably weighted to cause them to quickly fall to such positions. The office of the plates 32 85 is to effect a uniform horizontal arrangement or "evening" of the bags in the group, and also properly to locate the bags, as a group, transversely with relation to the heads 3 and 4, and for such purposes, after 90 the bags have been placed upon the sheet of paper which forms the wrapper, the plates 32 are swung to vertical positions in which they bear against the ends of the bags and push inward any bags which may 95 happen to project, thus insuring a uniform arrangement of all the bags. The compression of the group of bags to the desired density is, of course, produced by a movement of the head 4 toward the head 3; and in the 100 formation and securing of the package or bale the procedure is as follows: The operator first arranges the cords in the slots 28 and then lays the sheet which is to form the wrapper upon the platform 22 and over the 105 cords. Thereupon, he effects the movement of the head 4 to its advanced position and compresses the stack of bags. While the head 4 is held in its advanced position so as to maintain the bags under compression, he 110 folds the transversely disposed end portions of the wrapping sheet upon the bags, the folded portion at the rear of the package encompassing the spring bar 10. Thereupon, drawing the cords from the rear of 115 said spring bar over the package he ties the same to the free ends of the cords hanging from the slots 28 and then cuts the cords. He then returns the head 4 to its initial or retracted position and when said head 120 reaches such position he quickly removes the package from the machine by sliding it transversely beyond that side of the machine toward which the free end of the bar 10 projects, the machine then being ready for 125 another operation. In such sliding removal of the package the bar 10 serves as a guide and the web of the wrapper lying to the rear of said bar passes between the same and the abutment 14. When the package is re- 130

5 moved from the machine the natural re-expansion of the bags compensates for the space taken up within the wrapper by the bar 10 during the wrapping and tying operations and insures that the wrapper and cords shall have the requisite tightness.

10 The foregoing description deals with structural features which are old in the art but whose disclosure in this application will 15 promote an understanding of the features of utility and advantage of my present invention.

One feature of the invention consists in the provision of means located in the rear 15 of the platform 22 for holding the wrapping paper spaced from the bed plate. Such means preferably consists of leaf springs 34 which are disposed longitudinally of the bed plate 2 and, being yieldable under the 20 weight of the package, serve to hold the sheet of paper which provides the wrapper slightly spaced above said bed plate whereby the operator may readily grasp and manipulate said sheet in connection with the 25 folding and tying operations, as above described.

The plunger 9 reciprocates in a cylinder 35 and the invention includes means for supporting the somewhat heavily weighted 30 front end of the plunger during the movement thereof, thereby to insure that the spring bar 10 carried thereby shall always occupy a plane normal to the plane of the platform 22 and consequently to insure that 35 said bar, during its advance, shall bear uniformly throughout its area upon the stack of bags and shall effect a uniform compression of the said stack to the density required. This means preferably consists of 40 stabilizing arms 36 which are located at each side of and project rearward from the plate 8 and bear upon the bed plate 2. In the construction preferred, the arms 36 are provided at their ends with anti-friction 45 rollers 37 and the bed plate 2 is provided with rails 38 upon which said anti-friction rollers operate, the length of the rails 38 being selected to insure that the bar 10 will be supported, as described, throughout its 50 range of movement.

The cylinder 35 is, of course, disposed longitudinally of the table 2 and is provided with projecting attachment lugs 40 for cooperation with fastenings 41 by which said 55 cylinder is secured to the bed plate. It is preferred that the cylinder 35 shall be adjustable lengthwise of the bed plate 2, and for such purpose the bed plate is formed with longitudinal slots 41^a through which 60 the bolts of the fastenings 41 extend, the lengthwise adjustment of said cylinder being for the purpose of adapting the head 4 to packages of varying thickness.

The rear ends of the springs 34 are pref- 65 erably secured to the front pair of cylin-

der attachment lugs 40 by the nuts of the associated fastenings 41 and the free ends of said springs are preferably downwardly offset, as at 39, and, of course, bear upon the bed plate 2, the offsets 39 insuring that the 70 active portions of the springs shall project suitably above the upper face of said plate. Obviously, however, the springs 34 may be otherwise formed and arranged for the purposes in view.

75 The most important features of the invention are concerned with the co-operating relation of the plunger 9 and the cylinder 35 and the elements of the valve structure for controlling the operation of said plunger. The valve structure is preferably located at the rear end of the cylinder 35 and is connected to said cylinder whereby to admit air thereto for effecting the advance or retraction of the plunger and simultaneously 80 to exhaust the air used for the next previous stroke of the plunger. The plunger 9 has at its inner end a double piston, whose faces re-act to the air admitted for effecting the respective forward and rearward 85 strokes. The structural details of the said piston are ancillary features of the invention; and the piston preferably comprises a cupped member 42 which is fitted over the reduced rear end of the plunger and is secured thereto by screws 43 which also secure a flat ring or plate 44 employed for the retention of a rearwardly directed piston element 45 having sealing engagement with the wall of the cylinder 35; a similar, but 90 forwardly directed, piston element 46 is arranged at the front of the member 42 and is held by and between the same and a retaining ring 47 surrounding the plunger 9 and bearing against a shoulder 48 circumscribing 95 said plunger. The ring 47 projects slightly in advance of the margin of the element 46 and slightly beyond the circumference of the plunger 9 and protects the piston 46 against contact with the front 100 head of the cylinder. The flange 18 by engagement with the front head of the cylinder limits the rearward movement of the plunger and is arranged whereby the parts at the rear end of the piston will not contact 105 with the rear end of the cylinder when said plunger is fully retracted, the piston element 45 being thus protected. A soft leather cushioning piece or bumper 18^a is preferably arranged between said flange and the front 110 end of the cylinder. While a piston having the above or equivalent structural details is preferred, and, as stated, is an ancillary feature of the invention, it will be understood that other forms of pistons, constructed to serve the purposes in view, may be adopted, if desired.

115 The valve structure is preferably self contained and includes a casing 49 which has as its front end a circumscribing flange 120

50 whereby it may be attached by fastening screws 51 to the rear end of the cylinder 35. Said casing has an internal transverse vertical web 52 which provides a head or closure 5 for the rear end of the cylinder 35 and cooperates with the controlling valve 53. The casing 49 is extended rearward beyond the web 52 and its rear end is closed by a head 54 secured by screws 55. In the construction preferred, the valve 53 is formed 10 as a disk and is arranged in the rear of and concentric to the web 52, bearing against and cooperating with the rear face of said web, and is operated by an axially disposed stem 59. As shown, said valve has a rearwardly projecting boss 56 which is provided with a diametrical groove 57 and the head 54 is provided with a rearwardly extended bearing 58 for the stem 59, said stem having 15 at its inner end a head 60 which bears against the boss 56 and is formed with a diametrical tang 61 which fits closely in the groove 57 and by which the stem 59 and valve 53 are connected to rotate together. 20 The casing 49 is provided in the rear of the valve 53 and preferably at its lower side with an inlet connection 62 for live air; and the web 52 is formed with an exhaust duct 63 having a connection 64 externally 25 of said casing and leading from a main exhaust port 65 open to the rear face of the web 52. By virtue of the valve 53, the automatic operation of the press is completely 30 under the operator's control and may be effected with such rapidity as may be desirable. The function of the valve 53 is to provide for the admission of air into the cylinder 35 at either side of the piston and the exhaust of air from said cylinder at the 35 side of the piston opposite to that at which air is admitted, and in such function the valve 53 cooperates with the web 52, the various cooperating air passages in said valve and web being located at equal distances 40 from the common axial center. For the admission of air, the preferred construction comprises a live air port 67 extending between the flat faces of the valve 53 and live air passages 68 and 69 in the web 52, the passage 68 extending between the 45 flat faces of said web and communicating directly with the rear end of the cylinder 35 and the passage 69 having a lateral connection 70 with an air feed pipe 71 which communicates with the cylinder 35 at or near the 50 front end thereof. The valve 53 is operative in either of its extreme positions to pass live air to the cylinder 35 and thus provide for a movement of the plunger; in one of 55 said positions its port 67 aligns with the passage 68 and air for the operation of the plunger 9 is admitted in the rear of the piston, and in the other position its port 67 aligns with the passage 69 and air for the 60 operation of the plunger 9 is admitted in front of the piston. Simultaneously with the admission of air at either side of the piston, air is exhausted from the opposite side of the piston, and in the construction preferred the web 52 is provided with two 65 exhaust passages, 72 and 73, respectively, arranged at opposite sides of and equidistant from the port 65, the passage 72 having a lateral connection 74 with an exhaust pipe 75 which leads from the cylinder 35 70 near the rear end thereof and the passage 73 having a lateral connection 76 with an exhaust pipe 77 which leads from the cylinder 35 near the front end thereof; the passages 72 and 73 are open to the rear face of said 75 web and communication between each of them and the intermediate exhaust port 65 is established by a groove or channel 78 formed concentrically in the inner or front face of the valve 53. When the valve 53 is 80 positioned to align its port 67 with the passage 68 whereby to admit air to the rear of the piston, the channel 78 establishes communication between the passage 73 and the port 65 whereby the air in front of the piston will be passed to the exhaust duct 63. In like manner, when the valve 53 is positioned to align its port 67 with the passage 69 whereby to pass air to the cylinder 35 in front of the piston the channel 78 will connect the passage 72 and the port 65 whereby the air in the rear of the piston will be vented through the exhaust duct 63. 85 The pipe 77 is connected to the cylinder 35 at a point suitably in the rear of the front 90 end of said cylinder whereby an air cushion will be formed in the portion of said cylinder in advance of said pipe for the purpose of cushioning the forward stroke of the plunger 9 and protecting the press 95 against destructive shocks. For the same purpose, the exhaust pipe 75 is connected to the cylinder 35 at a point suitably in advance of the rear end of said cylinder, viz: the web 52, thereby to provide for an air 100 cushion against which the piston re-acts on its rearward stroke. In the construction preferred, the air cushion at the rear end of the cylinder is maintained only temporarily 105 in order not to impair the permissible speed 110 with which the press may be operated and the air forming said cushion is gradually vented until the cushion ceases to exist, thus allowing the piston to move rearward at a safe, but not too slow, degree until its movement is absolutely limited by the engagement of the flange 18 at the front end of the plunger 9 with the front end of the cylinder 35. For the purpose of gradually reducing or destroying the air cushion at the 115 rear end of the cylinder, the web 52 is provided with an exhaust passage 66 of very small diameter which extends from the front face of said web and is open to the 120 exhaust passage 72. Thus, on the rearward 125 movement of the piston, air is exhausted through the passage 66 and the air cushion is gradually reduced or destroyed. 130

stroke of the piston, there is first a rapid exhaust of air from the rear of the piston through the pipe 75 and passage 72 which continues until the piston passes the point 5 at which the pipe 75 is connected to the cylinder 35 upon which the air cushion becomes effective, greatly retarding the speed of rearward movement of the piston, and the air forming said cushion is slowly vented 10 through the exhaust passages 66 and 72. It will be manifest that the piston may move in either direction at high speed but that such high speed movement will have no destructive effect on the press owing to the air 15 cushions provided at the front and rear of the piston. It will also be manifest that since the air cushion at the rear of the piston does not prevent the full rearward movement thereof, the piston may have a long 20 operative stroke which is highly effective in instantly compressing the bags to the density desired and which does not require any sacrifice of compactness. The channel 78 preferably has an extent at least equal to 25 the spacing of the exhaust passages 72 and 73 whereby the exhaust through either of said passages in connection with the operation of the valve will be initiated prior to the alinement of the port 67 with the respective 30 passages 69 or 68, the venting of the air used for the previous stroke thus being accelerated with relation to the admission of air for the ensuing stroke.

Air pressure normally maintained against 35 the rear face of the valve 53 is effective to hold said valve in good working contact with the web 52. The operation of the valve is, of course, facilitated by regular lubrication; and for this purpose, the casing 49 40 may be provided in the rear of the valve 52 with an oil cup 79, while the valve 52 has a central oil passage 80 between its flat faces and open at the front face of said valve to a distributing channel 81, oil being fed 45 through said passage, under the action of the compressed air, to maintain the constant lubrication of the coöperating wearing surfaces of the valve 53 and web 52.

The operation of the valve 53 as above described may be effected by any suitable means but the construction disclosed is preferred by reason of its facility and certainty. As shown, the valve operating means consists of a longitudinal rock shaft 82 arranged under the bed plate 2 and journaled 50 in front and rear bearings 83 and 84, the bearing 83 being secured to the bed plate and the bearing 84 being formed in one with the head 54 of the casing 49, a flange or rib 55 extending between the bearing 84 and the bearing 58 for the valve stem 59. The valve stem 59 and rock shaft 82 are provided with coöperating gear segments 86 and 87, respectively, which are preferably adjust-

ably mounted; and the segment 86 is provided at its sides with stop lugs 88 for co-operation with the flange 85, said flange preferably carrying bumper elements 89 against which the lugs 88 impinge for the purpose of positively arresting the movement of the valve stem and valve in either direction. The shaft 82 is operated by parallel pedals 90 and 91, mounted at the rear of the frame 1 and projecting forward, one pedal operating said shaft in a direction opposite to the direction in which it is operated by the other pedal. The pedals 90 and 91 are operatively connected to the shaft 82 by chains 93 which are trained over a suitable sheave or drum 94 fast on said 75 shaft and have their terminal links secured by studs 95 which are, of course, removable and which project across the groove or channel in which the chains or cables 93 operate. The sheave or drum 94 is preferably rotatably adjustable relatively to the shaft 82 in order that the degree of rocking movement of said shaft in one direction or the other may be regulated as desired. For such purpose, the sheave 94 is connected by a 80 screw 96 to a suitably constructed clamp element 97 which surrounds the shaft 82 and may be set at any desired angular position on said shaft.

In the use of the machine, the only attention required on the part of the operator is the operation of the pedals 90 and 91, the other operations, apart from wrapping and tying, being entirely automatic. The organization is such that when either of the 100 pedals is operated air is immediately admitted into the front or rear end of the cylinder as the case may be and is vented from the opposite end of the cylinder and the piston is instantly responsive to the admission of air into the cylinder. The reciprocatory movements of the plunger 9 and head 4 are completely under the control of the operator and may be effected with great rapidity whereby the operation of compressing the 105 bags to the density desired may be completed in a second, while at the same time destructive shocks are substantially eliminated. The valve and cylinder organization is, moreover, readily accessible for any necessary purposes, such as renewing the valve faces, the piston elements, or the packing glands.

Having fully described my invention, I claim:

1. In a press of the type set forth, the combination of relatively movable coöperating heads for applying pressure, a bed plate over which the movable head operates, a resting surface at the front of the bed plate upon which the package is formed, and means associated with said plate in the rear of said resting surface and upon which a 120

sheet of wrapping paper may be held slightly spaced above said plate, as and for the purpose set forth.

2. In a press of the type set forth, the combination of relatively movable coöperating heads for applying pressure, a bed plate over which the movable head operates, a resting surface at the front end of the plate and upon which the package is formed, and leaf springs overlying said plate in the rear of said surface and upon which a sheet of wrapping paper may be held slightly spaced above said plate, as and for the purpose set forth.
- 15 3. In a press of the type set forth, the combination of a fixed head and a movable head, the latter having a pressure applying element for coöperation with the fixed head, means for projecting the movable head toward the fixed head, a bed plate over which the movable head operates, a resting surface at the front of the bed plate and upon which the package is formed, means associated with said plate in the rear of said resting surface and upon which a sheet of wrapping paper may be held slightly spaced above said plate, and arms secured to and projecting rearward from the movable head at each side of the center thereof and having supporting engagement with the bed plate, thereby positively to hold said pressure applying element in a plane at a constant angle to the plane of the bed plate.
- 20 4. In a press of the type set forth, the combination of a fixed head and a movable head, the latter having a pressure applying element for coöperation with the fixed head, means for projecting the movable head toward the fixed head, a bed plate over which the movable head operates, a resting surface at the front of the bed plate and upon which the package is formed, means associated with said plate in the rear of said resting surface and upon which a sheet of wrapping paper may be held slightly spaced above said plate, and arms secured to and projecting rearward from the movable head at each side of the center thereof and having supporting engagement with the bed plate, thereby positively to hold said pressure applying element in a plane at a constant angle to the plane of the bed plate.
- 25 5. In a press of the type set forth, the combination of a fixed head and a movable head, the latter having a pressure applying element for coöperation with the fixed head, means for projecting the movable head toward the fixed head, a bed plate over which the movable head operates, a resting surface at the front of the bed plate and upon which the package is formed, means associated with said plate in the rear of said resting surface and upon which a sheet of wrapping paper may be held slightly spaced above said plate, and means for supporting the movable head during its advance, from the bed plate, thereby positively to hold said pressure applying element in a plane at a constant angle to the plane of the bed plate.

plying element in a plane at a constant angle 30 to the plane of the bed plate.

4. In a press of the type set forth, the combination of a fixed head and a movable head, the latter having a pressure applying element for coöperation with the fixed head, 35 means for projecting the movable head toward the fixed head, a bed plate over which the movable head operates, a resting surface at the front of the bed plate upon which the package is formed, means associated with 40 said plate in the rear of said resting surface and upon which a sheet of wrapping paper may be held slightly spaced above said plate, and arms secured to and projecting rearward from the movable head at each 45 side of the center thereof and having supporting engagement with the bed plate, thereby positively to hold said pressure applying element in a plane at a constant angle 50 to the plane of the bed plate.

In testimony whereof I have hereunto set my hand in presence of two subscribing witnesses.
